CLAIM

The ornamental design for a pet feeder as shown and described.

DESCRIPTION

FIG. 1 is a perspective view of a first embodiment of a pet feeder showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the pet feeder where the pet feeder is in a configuration of use;

FIG. 10 is an enlarged view of portion 10 shown in FIG. 1;

FIG. 11 is a perspective view of a second embodiment of the pet feeder;

FIG. 12 is another perspective view thereof;

FIG. 13 is a front elevational view thereof;

FIG. 14 is a rear elevational view thereof;

FIG. 15 is a left side elevational view thereof;

FIG. 16 is a right side elevational view thereof;

FIG. 17 is a top plan view thereof;

FIG. 18 is a bottom plan view thereof; and,

FIG. 19 is a perspective view of the pet feeder where the pet feeder is in a configuration of use.

The dot-dash broken lines represent boundaries of the enlarged portion and form no part of the claimed design.
